Inventor:

W. E. Williams

UNITED STATES PATENT OFFICE.

WILLIAM ERASTUS WILLIAMS, OF WILMETTE, ILLINOIS.

SPLINT CARRIER FOR MATCH MACHINES.

Application filed December 16, 1918, Serial No. 267,034. Renewed March 10, 1924.

To all whom it may concern:

Be it known that I, WILLIAM ERASTUS WILLIAMS, a citizen of the United States, and a resident of Wilmette, county of Cook, and State of Illinois, have invented a new and useful Improvement in Splint Carriers for Match Machines, of which the following is a specification.

The object of my invention is to lighten the weight and lessen the cost of the splint carrier used in modern match making machines and the invention is set forth in the claims. Reference will be had to the accompanying drawing in which:

15 Fig. 1 is a plan, Fig. 2 a side and Fig. 3 an end view of a section of a splint carrier.

Fig. 4 is a sectional view, on an enlarged scale, showing the plate of the splint carrier being acted upon by dies and this constitutes the first operation in perforating the plate for carrying the splints.

Fig. 5 shows the dies and plate in the second operation.

Fig. 6 shows the third operation and

25 Fig. 7 the last operation.

Fig. 8 shows on an enlarged scale some match sticks or splints stuck into the carrier.

Fig. 9 shows the punches that discharge the matches from the carrier and this also is on an enlarged scale.

The match carriers that are generally used in the best machines are composed of perforated metal belts made up of links or sections of plates hinged together forming continuous endless carriers and the ends of the splints are forced into the perforations of the plates and are thus held for dipping and drying.

The sections of the metal belt have been made of iron and steel and are usually from three sixteenths to one quarter of an inch thick while the holes or perforations into which the splints are stuck are about one tenth of an inch in diameter.

45 It is impracticable to punch the perforations in metal that is thick enough to make a hole deep enough to properly hold the match sticks or splints. By my method of working in the holes in the metal I succeed in getting a hole the right depth to make a secure seat for the splint when using a plate one sixteenth of an inch or less thick. The holes have necessarily been drilled in the old

style plates while I may punch my holes and thus save enormously on the cost of making 55 the carrier.

As my carrier weighs less than one third of the old style carriers there is a saving in the first cost and in the operations or upkeep 60 of the machine.

In the drawing 1 indicates my match plate or carrier section for the splints. This plate is made of thin metal and has a flange 2 turned all around on its margin.

3 indicates rack teeth link bars secured to 65 the ends of the plates by any suitable means such as rivets spot welds or brazing or welding, not indicated in the drawing. The flange 2 of the plate 1 is imbedded in slots in the links 3 in order to retain the general 70 all around stiffness of the plate 1. By means of the links 3 the plates are connected into an endless carrier as desired. With same machine the plates are made larger and used more or less independently. 75

In Figure 4, 4 indicates the top die, 5 the lower die and 6 the punches that act on the plate and turn the flange 2 and emboss the cup shaped indentures 7 in the plate 1. These dies and punches cover an entire section in one operation. Were I to punch one hole or indenture at a time or one line of them at a time the operation of the next hole or line of holes would distort the previously 80 formed ones and make impossible the accurate registry required for the punches in discharging the matches.

By pressing the cup shaped indentures 7 as indicated I draw down the metal from the flat surface of plates providing for sufficient 85 stock for holes of the right depth to hold splints.

In the second operation Figure 5 with suitable dies 8 and 9 and punches 10 I narrow up the indentures 7 and yet preserve 90 their depth as indicated by the indentures 11.

In Figure 6 by dies 12 and 13 and punches 14 I pierce the indentures 11 and change 100 their form into those of 15 which thus affords a deep hole for the match splint end.

In Figure 7 with dies 16 and 17 and punches 18 I flange out the sharp projections of indentures 15 into the countersunk shape as indicated by 19. However if the holes are 105 made sufficiently accurate to each other and

the discharging punches are likewise accurate this last flanging operation of Fig. 7 may be omitted.

20 indicates the splints held in the carrier and in Figure 9, 21 indicates a series of punches adapted to enter the perforations and discharge the splints. The flanges or countersinks 19 guide slightly the entry of the punches 21 as they approach to discharge

10 the matches in the normal operation of the match machine.

Were I to undertake to draw down a hole of the depth required without first embossing a large cup as indicated by 7 the metal 15 would tear out and give a hole but little if any deeper than the thickness of the plate.

After the deep large cups have been embossed and closed in I may pierce the holes by drilling instead of punching them and

thus substitute drilling for the operation 20 shown by Fig. 6.

What I claim is:—

1. A match carrier plate of sheet metal having at its lateral margins integral stiffening flanges and having its body provided with numerous splint receiving perforations each surrounded by an integral annular flange.

2. A match carrier plate of thin sheet metal having at its lateral margins integral stiffening flanges, having its body provided with splint receiving perforations each surrounded with an integral annular flange on one face of the plate, and having each of its ends rigidly held by transverse laterally projecting link bars.

WILLIAM ERASTUS WILLIAMS.
